UNITED STATES PATENT OFFICE.

HARRY F. GEIST, OF RACINE, WISCONSIN, ASSIGNOR, BY MESNE ASSIGNMENTS, TO WEBSTER ELECTRIC COMPANY, OF RACINE, WISCONSIN, A CORPORATION OF WISCONSIN.

IGNITION SYSTEM.

1,271,030.

Specification of Letters Patent.

Patented July 2, 1918.

Application filed February 23, 1915. Serial No. 9,770.

To all whom it may concern:

Be it known that I, HARRY F. GEIST, a citizen of the United States, residing at Racine, in the county of Racine and State of Wisconsin, have invented certain new and useful Improvements in Ignition Systems, of which the following is a specification.

This invention relates to ignition systems for internal combustion engines.

10 One of the objects of the invention is to produce a mechanism suitable for operating an ordinary igniter plug and at the same time for operating the magneto which provides electric current for the plug, the mechanism being so arranged that the magneto can at any time be removed or replaced, or be left in place without operating, without in any way interfering with the operation of the igniter plug, or without requiring any 15 adjustments between the magneto inductor and its actuating member.

A further object of the invention is to produce a mechanism operatively connected to the magneto in a manner such that the 25 stresses tending to operate the rotor of the magneto are always rotational, the force tending to rotate or oscillate the motor always act at right angles to a line radial from the center of rotation of the rotor.

20 A further object of the invention is to produce a simple and efficient mechanism for operating simultaneously both the igniter plug and the magneto.

A further object of the invention is to 35 produce an ignition system when used in connection with a magneto that imparts an electrical ignition spark the volume and intensity of which is independent of the speed of the engine.

40 Further objects of the invention will be apparent from a consideration of the drawings attached hereto, and the description herein.

Figure 1 of the accompanying drawings 45 is an elevation of a magneto, an igniter plug and the operating mechanism therefor, which embodies the features of my invention. Fig. 2 is an elevation at right angles to Fig. 1. Fig. 3 is a cross section along the 50 line 3—3 of Fig. 1. Fig. 4 is a cross section along the line 4—4 of Fig. 1 showing a portion only of the mechanism, the movable parts thereof being in positions different from those shown in Fig. 3. Fig. 5 is a dia-

grammatic view of my magneto with a battery and an igniter.

In the drawings 1 indicates the igniter plug, mounted on the igniter block 2, which, by means of the flange 3, is fixed, in a usual manner, to the cylinder of the engine. Integral with the flange 3, or fixed thereto in any suitable manner, is the frame 4 of the operating mechanism 5 of the igniter plug and the magneto. Mounted on the frame 4 of the operating mechanism, by means of 65 bosses 6, is the magneto 7.

The magneto 7 may be of any suitable construction, the form which I prefer is fully illustrated and described in my co-pending application Serial No. 7979 filed 70 February 13, 1915, and reference may be had to said application for full information in regard thereto. I have shown diagrammatically in Fig. 5 so much of this preferred form of magneto as may be necessary for 75 the purposes of this application. The rotor 72 of the magneto when in operation, is oscillated by the operating mechanism in a manner hereinafter described. It is to be understood, however, that any other form 80 of oscillating magneto may be used in connection with my mechanism.

The igniter plug 1 comprises a fixed electrode 15, and a movable electrode 16. The movable electrode is fixed to an arm 17 projecting from a head 18 of a shaft 19 mounted in the frame 4 of the mechanism. And a further purpose of the mechanism 5 is to operate the shaft 19 so as to open at the proper time the circuit of the ignition system at the contact points of the electrodes 15 and 16. The fixed electrode 15 is connected in the circuit by means of the wire 17^a connected by means of the electric connector 18 and the nut 20 to the pin 19^a, 95 which is insulated from the frame 4 of the mechanism. The fixed electrode 15 is mounted on a head 21 of the pin 19. The movable electrode is electrically in contact with the frame 4, and hence is electrically 100 connected with the grounded ends of the ignition circuit in the usual manner.

The operating mechanism 5 comprises a shaft 25, which is mounted in the frame 4 coaxial with the shaft 26 of the magneto. 105 Rotatably mounted on the shaft 25 is a member 29 which comprises a push finger 30 and spring arms 31, each of the springs 32 has

one end fixed to a spring arm 31, and the other end fixed to a stud 33 of the framework, so that these springs at all times tend to hold the member 29 in the position of rest indicated by Fig. 3.

A push rod 34, reciprocated in any suitable manner by the engine, is guided by a roller 35 rotatably mounted on a pin 36. This push rod 34 when reciprocated is forced 10 against the push finger 30 and thus imparts a limited rotation to the member 29. Also rotatably mounted on the shaft 25 is a member 37, having a tooth 38 adapted to coact with a tooth 39 fixed to the member 29. An 15 arm 40 fixed to the member 37 carries a trip arm 41. The push rod 34, by any suitable resilient means (not shown), is normally held against the guide roller 35; but as the rod pushes against the finger 30, teeth 38 20 and 39 cause the member 37 to rotate, and the trip arm 41 by means of the arm 40, is carried against a trip roller 42 which is supported in a manner hereinafter described. The trip roller is thus forced against the 25 free end of the push rod 34, and the rod is thus pushed away from coaction with the finger 30, allowing springs 32 to force the member 29 quickly backward, to the position of rest. The inertia, however, of the 30 movable parts produces sufficient momentum to carry the member 29 backward beyond the normal position, for purposes to be hereinafter explained. The continual reciprocations of the rod 34 thus causes continual 35 oscillations of the member 29.

A member 45 rotatably mounted on the rotor shaft 26, has an arm 46 projecting outwardly and angularly therefrom. And the member 29 has an arm 47 projecting outwardly therefrom, and having a slot 48 in the outer end thereof. Within this slot the upper end 49 of the arm 46 passes, the arrangement being such that any oscillations of the member 29 impart corresponding 40 oscillations to the rotor 72 through the medium of the arms 47 and 46. The two members 29 and 45, together with the rotor 72, are fixed to their respective shafts so that at the limits of the oscillations of the rotor, 45 the rotor occupies the positions desired with reference to the poles of the magneto.

Evidently, by this arrangement, as the two shafts 25 and 26 are coaxial, the actuating stresses transmitted from the push rod to 50 the rotor, through the arms 47 and 46, are always rotational with reference to the rotor, that is they always act in a circular path concentric with the center of rotation of the rotor, and hence at right angles to 55 lines radiating from this center. By this means the loss of energy and the irregularities due to non-concentric or straight-line stresses are entirely eliminated.

Operation of the igniter plug is produced 60 in the following manner: Fixed to the pin

19 of the rotatable electrode is a member 55 having an outwardly and angularly extending arm 56. An adjustable set screw 57 is threaded into the outer end of the arm 56 and may be set in position by means of the 70 lock nut 58. The end 59 of the said screw projects from the arm 56 to a position which brings it in contact with the arm 47 as this arm is rotated backwardly by the springs 32 or as it passes beyond the position of rest 75 due to the springs. The screw 57 is so adjusted that such a contact is produced at a certain predetermined time with reference to the position of the rotor 72. The impulse given to the screw 57 by the arm 47 rotates 80 the member 55, the pin 19, and hence the arm 17, and thus opens the ignition circuit at the contact points of electrodes 16 and 15, the adjustment being such that this breaking of the circuit, and hence the production of the igniting spark, occurs at a time suitable for producing the explosion in the cylinder of the engine. A spring 60 prevents undesirable longitudinal movement of the movable electrode 16, and normally 85 holds the contact points of the two electrodes together.

In order to adjust the time of the spark to the particular position of the engine piston desired, an adjusting arm 61 is provided. 90 This arm is pivoted to the frame 4 by means of the pivot 62, and is adjustable on the frame so as to regulate the amount of engagement of the push rod 34 with the push finger 30. This adjustment is approximately 100 at right angles to the path of motion of the push rod. The pin 36 supports the guide roller 35 and is fixed firmly, by means of a boss 63, to lever 61. Mounted on this pin 36 is an arm 43 which carries the trip roller 42. When the arm 61 is moved to the position indicated by Fig. 3 the trip roller is thrown forward along the trip arm 41; and as the push rod 34 pushes against the finger 30 and thus rotates the member 29, the trip arm 41 will force the trip roller toward the free end of the push rod and the rod will be pushed away from coaction with the push finger 30. When the adjusting lever 61 is in this position this releasing action 110 will take place earlier than when the trip roller is thrown to the right by means of the lever. As a consequence the member 29 will be released more quickly, and in its backward oscillation will more quickly come in contact with the screw 57 so as to open the contact points earlier with relation to the position of the piston in the cylinder. This position of the lever 61 is therefore the 115 "advance" position. When the lever 61 is in the position 65 the spark is retarded with reference to the piston and hence this position is the "retard" position.

If for any reason it is desired to operate 120 the igniter plug without operating the mag- 125

neto, using a battery for a source of electric current, it is necessary only to disconnect the inductor of the magneto from the operating mechanism. This may be done by 5 removing the member 46 from the magneto shaft by taking out screws 70 and 71. Or if it is desired, the magneto may be entirely removed. In either of these cases the igniter plug will be operated by the mechanism, 10 exactly as if the magneto were in place. With the battery in parallel as indicated in Fig. 5, with the usual or any suitable operating switches, the ignition system may be supplied with electric current by the battery 15 or by the magneto, as desired, in the usual manner.

Although I have described with some particularity the preferred form of mechanism which embodies my invention, yet it is to be 20 understood that modifications therein may be made by those skilled in the art without departing from the spirit of my invention as disclosed by the following claims.

I claim as my invention:

25 1. Ignition apparatus of the class described comprising in combination with spark electrodes and a magneto, an oscillatory member arranged when operated to impart movement to said magneto and the 30 movable spark electrode, a reciprocating push rod arranged successively to engage, move and release said oscillatory member and means operated by said oscillatory member for releasing the latter from the push 35 rod.

2. Ignition apparatus of the class described comprising in combination with spark electrodes and a magneto, an oscillatory yoke, springs normally retaining said 40 yoke in a certain position, such oscillatory yoke arranged when actuated to operate said magneto and the movable spark electrode, a reciprocating push rod arranged successively to engage, move and release said oscillatory yoke, and means operated by said 45 yoke for releasing the latter from the push rod.

3. Ignition apparatus of the class de-

scribed comprising in combination with spark electrodes and a magneto, an oscillatory member arranged when operated to impart movement to said magneto and the movable electrode, a reciprocating push rod adapted successively to engage, move and release said oscillatory member, means operated by said oscillatory member for releasing the latter from the push rod, and devices for varying the time at which said last mentioned means is operated by the oscillatory member.

4. Ignition apparatus of the class described comprising in combination with a magneto, an oscillatory member, springs normally retaining the oscillatory member in a certain position, said oscillatory member arranged to impart movement to said magneto, a reciprocating push rod arranged successively to engage, move and release said oscillatory member, means operated by said oscillatory member for releasing the latter from the push rod, and mechanism for varying the time at which said last mentioned means is operated by the oscillatory member.

5. Ignition mechanism of the class described comprising a frame carrying a magneto and spark electrodes, a yoke mounted on the frame arranged when actuated to operate said magneto and electrodes, springs normally retaining said yoke in a certain 80 position, a push rod arranged successively to engage, move and release said yoke a tooth on said yoke, a member mounted on axially with said yoke and having a laterally 85 extending arm and a tooth co-acting with the tooth of the yoke and a pivoted arm carried by the frame disposed in the path of said laterally extending arm and lying under the push rod.

In testimony whereof, I hereunto set my 90 hand in the presence of two witnesses.

HARRY F. GEIST.
